[57] CLAIM

The ornamental design for a mouthguard, as shown and described.

DESCRIPTION

FIG. 1 is a perspective view of a mouthguard showing my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom view thereof; and,

FIG. 7 is a cross sectional view thereof, the same being taken substantially along line 7—7 of FIG. 5.

The left side elevational view is a mirror image of the right side elevational view shown in FIG. 4 and the view in the direction opposite line 7—7 is the mirror image of the view shown in FIG. 7.
